US0D1042486S

(12) **United States Design Patent** (10) Patent No.: **US D1,042,486 S**
(45) Date of Patent: ** Sep. 17, 2024

(54) **DISPLAY SCREEN OR PORTION THEREOF HAVING A GRAPHICAL USER INTERFACE**

(71) Applicant: **R1 Learning LLC**, Arlington, VA (US)

(72) Inventor: **Thomas P. Karl**, Arlington, VA (US)

(73) Assignee: **R1 LEARNING LLC**, Arlington, VA (US)

(**) Term: **15 Years**

(21) Appl. No.: **29/826,711**

(22) Filed: **Feb. 15, 2022**

(51) LOC (14) Cl. **14-04**

(52) U.S. Cl.

USPC **D14/485**

(57) **CLAIM**

The ornamental design for a display screen or portion thereof having a graphical user interface, as shown and described.

DESCRIPTION

The FIGURE is a front view of the display screen or portion thereof having a graphical user interface showing my new design.

The broken lines showing the display screen or portion thereof form no part of the claimed design.

The remaining broken lines showing portions of the graphical user interface form no part of the claimed design.

1 Claim, 1 Drawing Sheet
